CLAIM

The ornamental design for a front panel for horizontal computer, as shown and described.

DESCRIPTION

FIG. 1 is a front elevational view of a front panel for horizontal computer showing our new design;

FIG. 2 is a left end view of the front cover;

FIG. 3 is a right end view of the front cover;

FIG. 4 is a top plan view of the front cover;

FIG. 5 is a back elevational view of the front cover; and,

FIG. 6 is a bottom plan view of the front cover.

The broken lines are shown for illustrative purposes only and form no part of the claimed design.
